UNITED STATES PATENT OFFICE.

CHARLES WACHTEL, OF JAMAICA, NEW YORK.

SPARKING IGNITER.

1,123,434.

Specification of Letters Patent.

Patented Jan. 5, 1915.

Application filed May 16, 1913. Serial No. 768,054.

To all whom it may concern:

Be it known that I, CHARLES WACHTEL, a citizen of the United States, residing at Jamaica, county of Queens, and State of New York, have invented certain new and useful Improvements in Sparking Igniters, of which the following is a specification.

One of the principal objects of this invention is to provide a sparking igniter in which a torch is provided to be ignited by the sparks from a suitable sparking metal, the torch being so constructed that by moving it sharply over the sparking material, sparks of sufficient intensity to light the torch will be produced.

Another object of the invention is to provide a suitable receptacle for the torch, the torch being provided with suitable non-combustible absorbent material at its end and the receptacle being so constructed that said absorbent material will be saturated with a readily inflammable material.

Another object of the invention is to so construct the torch and its receptacle that when the torch is withdrawn from the receptacle any surplus moisture or inflammable fluid will be wiped therefrom leaving the absorbent portion of the torch saturated to the proper degree to be readily ignited by the sparks produced by wiping or scratching the torch along the sparking material.

Another object of the invention is to provide a spark producing device of the proper construction so that when it is drawn over or scratched on the sparking material, sparks will be produced to ignite the torch.

There are other objects and advantages of the invention which will appear herein-after.

In the drawing, Figure 1 is a plan view of an igniter showing a plurality of sparking blocks, the igniter base being in the form of a cigar-ash tray; Fig. 2 a vertical sectional view of the igniter shown in Fig. 1; Fig. 3 a side elevation, partly in section, of the torch; Fig. 4 an elevation of the igniter in a slightly different form and adapted to be attached to a wall or other support; and Fig. 5 a detail transverse sectional view of one of the flanged channels for containing the sparking blocks.

Referring to the various parts by numerals, 1 designates the base of the igniter, which as shown in Figs. 1 and 2, is in the form of a cigar-ash tray. This base is of

sufficient weight to hold the device stationary while the torch is being scratched on the sparking blocks, as will be more fully hereinafter described. The base is provided with a central vertical post 2 which is provided on its upper surface with a concave recess lined with a suitable flexible material and adapted to receive the bulb 3 of the reservoir 4. The reservoir is adapted to contain an inflammable fluid such as alcohol, benzine or the like, and consists of the bulb 3 and the upper elongated tubular portion 5. The upper end of the portion 5 is supported in a cylindrical cap 6 which is provided at its upper end with the top plate 7. Rigidly connected to this cap 6 are three downward extending rigid arms 8 whose lower ends are rigidly connected to the central post 2. These arms form a cage which surrounds the reservoir and protects it, and said reservoir is preferably formed of glass or other transparent material so that the amount of fluid in the bulb 3 may be observed at all times.

In the portion 5 of the reservoir is secured an elongated tubular wick 9 whose lower end extends a short distance into the bulb 3. Connected to this lower depending end of the tubular wick is a feeding wick 10 which extends to the bottom of the receptacle 3 and feeds the liquid therein to the tubular wick. Within the tubular wick at the lower end of the cylindrical part 5 of the reservoir is secured a transverse partition or diaphragm 11, said diaphragm being provided with an upwardly extending marginal flange by which it is frictionally engaged with and maintained in the wick. This diaphragm is provided with two small perforations to permit the fumes or vapors from the fluid within the bulb 3 to pass upwardly to the torch and to permit the fluid to pass downwardly into the bulb when the device is charged or filled. Rigidly secured in the top plate is a depending sleeve 12 the inner diameter of said sleeve being precisely the same as the inner diameter of the tubular wick, said sleeve serving to protect the upper end of the wick and to hold it permanently in position.

The torch and sparking device consist of a cylindrical sleeve 13 in which is rigidly secured, by any suitable means, absorbent non-inflammable material 14. This material fills the sleeve 13 and extends beyond the open end thereof a suitable distance

2

and said projecting end is of slightly larger diameter than the diameter of the containing sleeve 13. I preferably form this filling material or torch proper of asbestos wicking 5 which will readily absorb the inflammable material but which is non-inflammable and practically indestructible. This non-inflammable and absorbent material extends up into the sleeve 13 a suitable distance and 10 serves, when saturated, to hold the reserve or surplus moisture which will be supplied to the exposed end of the torch when the supply of fluid in the reservoir and the wick 9 is reduced below the point necessary for 15 the saturation of the torch. The torch fits closely in the tubular wick 9 so that as said torch is drawn from the receptacle the wick serves as a wiper to remove from the torch any surplus moisture thereon. The exposed 20 end of the absorbent material is slightly larger in diameter than the containing sleeve 13 and said sleeve 13 is slightly smaller in diameter than the interior of the tubular wick 9 so that the torch proper will 25 contact with the wick and the sleeve 13 will be held out of contact therewith. The upper or outer end of the sleeve 13 is provided with an inwardly and downwardly tapered collar 15 which is adapted to fit 30 snugly in the upper end of the sleeve 12 and to thereby seal the receptacle 14 and prevent the escape of the vapors of the inflammable material contained within the receptacle. This collar serves to center the upper 35 end of the torch and assist in preventing the sleeve 13 contacting with the wick 9. The outer end of the torch is provided with a head 16 by which it may be grasped and manipulated. Extending longitudinally 40 through the torch and projecting beyond the inner end 14 thereof is a pin 17 which carries at its projecting end an upwardly and inwardly beveled sparking head 18 formed with a sharp peripheral cutting 45 edge. This head is formed close to the exposed end of the absorbent torch 14 but is sufficiently distant therefrom to permit said head to be brought into contact with the sparking material without bringing the absorbent portion of the torch against said 50 material, as will be more fully hereinafter described. The beveled head 18 with its sharp edge is especially designed for the purpose of producing intense sparks by 55 slight but rapid movement of said head on the sparking material.

The receptacle support carries the sparking blocks, suitable holders being provided for this purpose. Each holder consists of 60 a long channel vertically disposed and formed with side walls 19 and the bottom wall 20. The side walls are bent inwardly slightly, as at 21, to lock the sparking block 22 in position in said channel. The side 65 walls beyond the sparking blocks and be-

ginning at the outer surface of said blocks extend outwardly and form diverging flanges 23 said flanges extending the entire length of the sparking blocks. The upper ends of the channels are closed by a cap 70 piece 24 which extends outwardly over the channel and over the space between the flanges 23. There is no cap or closure at the lower end of the channel so that the 75 sparking blocks may be removed and so that the torch may be scratched or swiftly moved over the surface of the sparking block and pass out of the channel at the lower end thereof. The flanges 23 are for the purpose of guiding the torch and preventing the spreading of the sparks and also to deflect them back to the torch. The purpose of this is to concentrate the sparks and direct them toward the torch, thereby insuring the ignition of the absorbent end of 80 the torch. The plate 24 closing the upper end of the channel containing the sparking block prevents the operator placing the head 18 on the top of the block. This plate 85 also forms a stop and guide so that the 90 operator may readily place the scratching head of the torch close to the upper end of the sparking block without any risk of placing the head on the top of the sparking block or of moving the block downwardly 95 out of its channel. The channels for containing the sparking blocks are shown in Fig. 1 as supported on the arms 7. It is obvious, however, that they may be secured at any place on the support.

100 The device shown in Fig. 4 is adapted to be attached to a wall or other vertical support. In this form of the device the receptacle 4^a is secured to the base or back plate 1^a and the channel 19^a for supporting 105 the sparking block 22^a is mounted directly on the base plate 1, otherwise the receptacle and torch are constructed precisely as shown in Fig. 2.

110 What I claim is:

1. A sparking igniter comprising a support, a receptacle mounted thereon, a tubular wick in said receptacle, a torch adapted to extend near to the lower end of the tubular wick and formed with an absorbent portion at its lower end adapted to fit the tubular wick, a sparking-head at the lower end of the torch in close proximity to the absorbent portion thereof and formed with a sharp cutting edge, a long sparking block, means 115 for supporting said sparking block adjacent the receptacle, outwardly extending flanges along the edges of said sparking block, and a plate to cover the upper end of the sparking block.

120 2. A sparking igniter comprising a support, a receptacle mounted thereon and formed with a narrow tubular portion, a wick in said tubular portion, a torch adapted 125 to extend near to the lower end of the said 130

tubular portion of the receptacle and formed with an absorbent portion at its lower end adapted to contact with the wick when the torch is placed in the receptacle, means carried by the torch for sealing the receptacle at the upper end thereof, a sparking-head at the lower end of the torch adjacent the absorbent portion of the torch, and formed with a sharp cutting edge at its lower end,

a long sparking block adjacent the receptacle and adapted to be engaged by the sparking head of the torch.

In testimony whereof I hereunto affix my signature in the presence of two witnesses.

CHARLES WACHTEL.
